CLAIM

The ornamental design for an electric grinder, as shown and described.

DESCRIPTION

FIG. 1 is a perspective view of an electric grinder showing the new design.

FIG. 2 is a front view of the electric grinder of FIG. 1.

FIG. 3 is a rear view of the electric grinder of FIG. 1.

FIG. 4 is a side view of the electric grinder of FIG. 1.

(Continued)

FIG. 5 is an opposite side view the electric grinder of FIG.

1.

FIG. 6 is a top view the electric grinder of FIG. 1; and,
FIG. 7 is a bottom view the electric grinder of FIG. 1.

1 Claim, 7 Drawing Sheets

FIG. 1

FIG. 2

FIG. 3

FIG. 4

FIG. 5

FIG. 6
